UNITED STATES PATENT OFFICE.

HENRY A. TELLESON, OF OAKLAND, CALIFORNIA.

DISPENSING-RECEPTACLE.

936,187.

Specification of Letters Patent.

Patented Oct. 5, 1909.

Application filed August 25, 1908. Serial No. 450,183.

To all whom it may concern:

Be it known that I, HENRY A. TELLERSON, a citizen of the United States, residing at 5 Oakland, in the county of Alameda and State of California, have invented certain new and useful Improvements in Dispensing-Receptacles, of which the following is a specification, reference being had therein to the accompanying drawing.

10 This invention relates to improvements in dispensing receptacles, and particularly to an oil can, and has for its object the provision of means for facilitating the closing of the discharge spout or opening, and 15 also the manipulation of said closing means.

Another object of the invention is the peculiar construction of valve-means and the means for operating said valve means.

With these and other objects in view, the 20 invention consists of certain novel constructions, combinations, and arrangements of parts as will be hereinafter fully described and claimed.

In the drawings: Figure 1 is a vertical, 25 sectional view of a device constructed in accordance with the present invention. Fig. 2 is a similar view, showing the same in an inverted position. Fig. 3 is a plan view of the detachable guide. Fig. 4 is an enlarged, fragmentary view of the stem and the set-collar. Fig. 5 is a sectional view taken on line 5, 5, Fig. 1.

Referring to the drawings by numerals, 30 1 designates the body of the receptacle or can, which is provided with a bottom 2 formed of flexible or springy metal, whereby the bottom can be compressed for actuating the valve-device hereinafter described, and which bottom will readily expand and 35 assume its normal position as shown in Fig. 1.

A spout 3 is threaded, at its lower end, into the internally-threaded neck 4 of the body 1, and near the discharge-end 5 of the spout and formed on the inner walls of said 40 spout is an inwardly-extending, annular valve-seat 6; between the valve-seat 6 and the outer end of the spout 3 is positioned the enlarged portion 7 of stem 8; said enlarged portion 7 constitutes a valve-member 45 adapted to be normally seated on seat 6. The stem 8 terminates at its lower end contiguous to the bottom 2, whereby when the bottom 2 is compressed, stem 8 will be slid longitudinally of the spout 3, for removing 50 valve-portion 7 off of the valve-seat and opening the spout. The stem 8 is slid upon or

journaled in a primary, detachable guide 9 and an auxiliary guide 10. The guide 9 is provided, preferably, with an enlarged portion 11, Fig. 3, within which enlarged portion 11 is formed an aperture for receiving the stem 8. Contiguous to the ends of the guide 9 are formed apertures 12, through which extends the detachable fastening means, as for instance, screws 13^a, whereby the guide 9 is detachably secured to the lower end of the spout 3, as the screws 13^a are threaded into threaded sockets formed in the lower end of said spout. The auxiliary guide-member 10 is formed of a narrow 60 elongated strip which has its ends rigidly secured to the spout, the central portion of which has an opening formed through it for the passage of the stem 8. Said guide 70 10 extends transversely across the spout and as it is comparatively narrow, it will not interfere with the flow of the liquid through 75 the spout.

Positioned between the guides 9 and 10, and mounted upon the stem 8, is a collar 13, 80 which is held in an adjusted position upon said stem by, preferably, a set-screw 14, whereby the life of spring 15 will be greatly increased, thereby minimizing the cost of 85 keeping the dispensing receptacle or can in an efficient condition, as it will be obvious that if the spring becomes weak, by adjusting the set-collar 13 upon the stem 8, the tension of the spring can be increased whereby the valve-portion 7 will always be held 90 in a closed position prior to the operator pressing upon the bottom 2. The spring 15 presses, at one end, against the auxiliary 95 guide 10, and at its other end, against the set-collar 13.

It is to be noted that the primary guide-member 9 is of less length than the diameter of the lower end 16 of the spout 3, thereby permitting the spout to be quickly removed off of the neck 4 of the body 1, when it is 100 desired to either fill the body with the liquid or to assemble or disassemble the parts of the valve-device or adjust the tension of the spring.

In Fig. 2, I have shown the can or dispensing receptacle in an inverted position, and also the parts of the valve in an open position, for permitting the liquid to flow outward or be discharged through the spout 3. The bottom 2 is shown in a compressed 110 position, for actuating stem 8, but as soon as the pressure is removed from bottom 2, the

bottom will spring back to the position shown by dotted lines 2^a, and owing to spring 15 pressing upon the set-collar 13, the valve will be quickly seated upon its seat.

5 What I claim is:

A device of the character described comprising a body having a compressible bottom, a spout detachably secured to said body and having a valve seat adjacent its discharge end, a rod slidably mounted in said spout and having one end in engagement with the compressible bottom, and its other end provided with a valve controlling the discharge through said spout, a detachable

guide for said rod carried by the inner end 15 of the spout, an intermediate guide carried by and rigid with the spout, an abutment adjustably mounted on the rod between said guides, and a spring coiled about said rod and interposed between the adjustable abutment and the intermediate guide.

20 In testimony whereof I, hereunto affix my signature in presence of two witnesses.

HENRY A. TELLERSON.
